UNITED STATES PATENT OFFICE.

LE GRAND PARISH AND ROSCOE B. KENDIG, OF CLEVELAND, OHIO.

DOOR-STOP.

No. 926,595.

Specification of Letters Patent.

Patented June 29, 1909.

Application filed May 26, 1908. Serial No. 435,165.

To all whom it may concern:

Be it known that we, LE GRAND PARISH and ROSCOE B. KENDIG, of Cleveland, in the county of Cuyahoga and State of Ohio, have invented certain new and useful Improvements in Door-Stops, of which the following is a specification.

This invention has reference to devices for engaging the edges of car doors or other analogous structures wherein the door in closed position abuts against a stop provided therefor to limit the motion of the door, and to aid in the efficient locking of the same.

15 The principal object of this invention is the provision of a stop device of the character specified, which will be more durable than those heretofore commonly employed, and which will act as a more secure and rigid 20 stop for the door than the common wooden stop ordinarily employed, and which further may be readily detached from the car when access is had to the interior thereof, but cannot be readily detached from the 25 outside when the door is closed.

Another object of the invention has reference to the provision of a stop of this character which can be very easily applied to cars which are already in service, and thus obtain 30 the advantages of the improvement, without seriously interfering with the operation of the cars, or requiring very much expense.

The above, as well as such other objects 35 as may hereinafter appear, we attain by means of the construction which we have illustrated in preferred form in the accompanying drawings, wherein—

Figure 1 shows in side elevation a view of 40 our improved stop in position at the side of the car door;

Figure 2 is an enlarged view of the major portion of the stop device proper;

Figure 3 is another view of the device, 45 showing in one portion in section an arrangement whereby the securing bolts are held in place;

Figure 4 is a sectional view on the line IV—IV of Figure 2, and

50 Figure 5 is a sectional view indicating the construction of lock device which we prefer to use in connection with this improved door stop.

Referring more particularly now to Figures 2 and 3, it will be seen that in carrying out our invention, we provide first a metal

body portion 6 having a projecting bracket or part 7 provided with an opening 8 for the insertion of an attaching bolt, and another projecting part 9 shown more plainly perhaps in Figure 4, adapted to guide the door into place when it is closed. As clearly indicated in Figure 4, the body portion is formed of a hollow shell 10 preferably rectangular and of metal, and is arranged at each end as shown in Figures 2 and 3, to receive the adjacent ends of the wooden stops 11 which are secured to the intermediate portion of the stop 6, by means of suitable bolts such as are indicated at 12, and extend preferably to the upper and lower edges of the door, as indicated in Figure 1, such wooden stop being substantially similar to the stops ordinarily employed which extend the full length of the side of the door, but which in case our improvement is applied on a car provided with the old wooden stop, will be cut at a point intermediate the ends to allow the insertion of such improved form of stop device.

In order to secure the stop to the door post 13, we provide slotted notches 14 (see Figures 2 and 3) into which are inserted the bolts 15 that pass through the post and are secured by nuts 16 upon the interior of the car, the heads 17 of the bolts being kept from turning by the flanges 18 indicated in Figure 4, and the bolt heads abutting on the top thereof against a rib or projection 19 as also indicated in said Figure 4.

In practice we prefer to arrange the slotted openings in which the bolts 15 are secured, so that as indicated in Figure 2, at least two of them are opposite each other—thus for example 14 and the slot marked 20 extend in opposite directions so that the bolts engaging said slotted openings will have to be put in place before the stop device is attached to the car, and the said bolts then after being inserted through the openings in the door post can not in any manner be taken out from the outside of the car, but only taken out all together by taking the whole stop off the side of the car after taking off the nuts 16 on the inner ends of the bolts, inside the car. In the construction shown we have indicated three such slotted openings, the third one being marked 14a.

In the preferred construction of our improvement we provide the metal body portion of the stop with a projection 21 to which is pivoted a locking device 22 adapted

to engage a hasp or other securing mechanism, and extending downward when in locked position, through a projection 23, with a slot provided in the member 22 whereby, as indicated at 24, a car seal may be readily employed. It is obvious that other locking means may be substituted for the one described, if desired, however, and in the described contemplation of our invention we do not desire to be restricted to the precise locking which may be used. Neither is it essential that the locking device be cast integral with the door stop, as it may be secured to it by rivets or other suitable means.

As heretofore most commonly constructed, the stops employed in devices of this character have been made of wood and bolted to the car body at the edge of the door opening, the bolts passing through the stops. These stops have proven generally unsatisfactory, as the wood in many cases becomes split by reason of the impact of the door, due to careless or too vigorous closing, and in other instances the bolts holding the stop become bent backwards so that a tight fit between the door and the stop becomes impossible. Again trouble is often experienced in the use of wood stops, by the warping of the wood or the enlargement of the bolt holes, due to shrinkage, allowing the stop to become loose and ineffective in securing the desired tightness of the joint between the door and the stop.

The provision of the bracket or projection 7 formed integral with the body portion of the stop insures much more stable bracing against impact of the door, and effectively resists the tendency of the stop to turn backward. Obviously a plurality of such braces could be used if desired.

Having thus described our invention and illustrated its use, what we claim as new and desire to secure by Letters Patent, is the following:

1. A stop for car doors comprising a main or body portion of metal, said body portion being provided with fastening means for the door and with engaging bolts having their heads locked within the body portion and inaccessible from the outside of the car to which the stop is attached. 45

2. A stop for car doors comprising a metal portion provided with engaging bolts having their heads locked within the body portion and inaccessible from the outside of the car, fastening means for the door upon the metal portion, and a brace or strut upon the metal portion for supporting the stop. 55

3. A stop for car doors comprising a main or body portion of metal and a supplemental wood portion, said body portion being provided with fastening means for the door and with engaging bolts having their heads locked within the body portion and inaccessible 60 from the outside of the car to which the stop is attached. 65

4. The combination with a car door provided with a fastening member, of a stop comprising a body portion of metal provided with means for co-operating with the fastening means on the door and with a rearwardly projecting metal strut or bracket, and a supplemental wood portion. 70

In testimony whereof we have hereunder signed our names in the presence of the two 75 subscribed witnesses.

LE GRAND PARISH.
ROSCOE B. KENDIG.
